UNITED STATES PATENT OFFICE.

MATHIAS B. WONSOMS AND JENS P. SCHONBOE, OF AUDUBON, IOWA.

IRONING-BOARD.

No. 899,091.

Specification of Letters Patent.

Patented Sept. 22, 1908.

Application filed October 25, 1907. Serial No. 399,150.

To all whom it may concern.

Be it known that we, MATHIAS B. WONSOMS and JENS P. SCHONBOE, citizens of the United States, residing at Audubon, in the county of Audubon and State of Iowa, have invented a certain new and useful Ironing-Board, of which the following is a specification.

The object of our invention is to provide an ironing board of simple, durable and inexpensive construction, so constructed as to normally stand in a folded position within a suitable cabinet or casing, with its lower end at the bottom of the casing, and also so constructed that it may be quickly and easily moved to a horizontal position at any desirable degree of elevation, and there automatically held and supported for use as an ironing board.

More specifically it is our object to provide means whereby, when the board is moved from its folded or vertical position, to its position for use, the operator need only move the inner end to the desired point of elevation, whereupon the outer end will be automatically secured, and firmly supported in position in line horizontally with the inner end, thus making it impossible for the board to assume other than a horizontal position at any point of elevation.

Our invention consists in the construction, arrangement and combination of the various parts of the device, whereby the objects contemplated are attained, as hereinafter more fully set forth, pointed out in the claims, and illustrated in the accompanying drawings, in which—

Figure 1 shows a sectional view of a cabinet containing our improved ironing board, showing the ironing board in its folded position. Fig. 2 shows a front elevation of the cabinet containing the ironing board in a folded position, with the door of the cabinet open. Fig. 3 shows a view similar to Fig. 1, with the ironing board in its horizontal position ready for use. Fig. 4 shows a sectional view on the line 4—4 of Fig. 1, and Fig. 5 shows a sectional view on the line 5—5 of Fig. 3.

Referring to the accompanying drawings, we have used the reference numeral 10 to indicate the cabinet or casing. This is designed to be secured to a suitable stationary support, such for instance as a wall. It is provided at its front with a hinged door 11 having a latch 12. On the sides of its in-

terior are two parallel guide strips 13, spaced apart and extended from the bottom of the cabinet to a point above the center thereof.

The ironing board proper is indicated by the reference numeral 14, and is of the ordinary contour and size, and is provided on one end with a cross piece 15, which cross piece has its ends projected into the space between the guide strips 13, and said cross piece is of a width to accurately fit between the strips 13, but its thickness is much less than its width, so that when the ironing board is in a horizontal position, as shown in Fig. 3, the cross piece will accurately fit between the strips 13, and when the ironing board is in a vertical position as shown in Fig. 4, the cross piece will freely slide between the strips 13. Secured to the under surface of the ironing board is a rack 16, and fixed to the under surface of the board, between the rack 16 and the cross piece 15 is a flexible chain 17. Mounted upon the cross piece 15 are two lugs 18 spaced apart, and having pivoted to them the rods 19. Mounted upon the base of the cabinet are two lugs 20 spaced apart and having pivoted between them the arm 21, which arm has a pointed end 22 designed to engage the rack 16. Rods 19 are pivoted to the central portion of the arm 21.

In practical operation, the ironing board is normally retained within the cabinet in the position shown in Figs. 1 and 2, and when in this position, the cabinet door may be closed, and the entire device will occupy very small space. When it is desired to use the ironing board the operator opens the cabinet door and grasps the ironing board. He then tilts it forwardly, and then bodily moves it upwardly until the lower end is at the point of elevation where it is desired to place the ironing board for use. This upward movement of the ironing board may be readily and easily accomplished, because the surfaces of the guide strips 13 that engage the cross piece 15 are smooth, and the cross piece will freely slide between them. The operator then swings the outer or free end of the board downwardly, thus causing the rods 19 to move the arm 21 inwardly to such a position that when the outer end of the ironing board is moved down to a horizontal position, the arm 21 will then engage the rack 16, and thus firmly hold the ironing board in position.

When the ironing board is in position hori-

zontally, the cross piece 15 will firmly engage the adjacent surfaces of the guide strips 13, and thus hold the ironing board against outward and inward movement. The arm 21 5 will hold the outer end of the ironing board against downward movement, and the rods 19, which are connected with the arm 21 and also with the inner end of the board, will hold the inner end against both up and down 10 movement, so that the board is firmly supported. If it is desired to adjust the position of the ironing board, to either raise or lower it, this may be done by tilting the outer end of the board upwardly until it is free 15 from the arm 21, and then moving the inner end to the desired point of elevation, and then permitting the outer end to move down to a horizontal position, and in any position of the adjustment of the ironing board 20 proper, the arm 21 will be held by the rods 19 to the proper position for supporting the board horizontally.

The chain 17 is fixed at one end to the outer portion of the arm 21, and is of such length 25 that when the ironing board is in the position shown in Fig. 1, the arm 21 will be held in a substantially vertical position so that the cabinet door may be closed without the necessity of the operator touching the arm 21.

Having thus described our invention, what we claim and desire to secure by Letters Patent of the United States, therefor, is,

1. In a device of the class described, the combination of an ironing board, a sliding support for the inner end thereof, an arm pivoted to a stationary support, and a rod pivoted to the inner end of the ironing board and to the said arm, said rod serving to control the position of the arm relative to that of the

board, and also serving as a brace for the inner end of the ironing board, and a rack fixed to the ironing board to be engaged by said arm. 40

2. In a device of the class described, the combination of an ironing board, a sliding support for the inner end thereof, an arm pivoted to a stationary support, and a rod pivoted to the inner end of the ironing board and to the said arm, said rod serving to control the position of the arm relative to that of the 45 board, and also serving as a brace for the inner end of the ironing board, and a chain fixed to the ironing board and to the said arm in such a manner as to move the arm upwardly and inwardly when the ironing board is 50 placed in a substantially vertical position with its lower end adjacent to the pivot point of said arm.

3. In a device of the class described, the combination of a cabinet, guide strips on the 55 sides of the cabinet spaced apart, an arm pivoted to the cabinet, an ironing board, a cross piece fixed to the ironing board with its ends between said guide strips, said cross piece being of such shape as to engage the strips when the ironing board is in a horizontal position, and to freely slide between them when the ironing board approaches a vertical position, a rack secured to the ironing board to be engaged by said arm, and rods pivoted to the 60 inner end of the ironing board, and the central portion of said arm.

Des Moines, Iowa, Oct. 2, 1907.
